Fixture for Supporting Display Cards

Lloyd Harter, Pittsburg, Ohio

Application April 14, 1954, Serial No. 30,014

Term of patent 14 years

(Cl. D80—9)

To all whom it may concern:

Be it known that I, Lloyd Harter, a citizen of the United States and a resident of Pittsburg, Darke County, Ohio, have invented a new, original, and ornamental Design for a Fixture for Supporting Display Cards, of which the following is the specification, reference being had to the accompanying drawing, forming a part thereof, wherein:

The broken lines shown in Figure 1 are for illustrative purposes only.

I claim:

The ornamental design for a fixture for supporting display cards, substantially as shown and described.
